F. S. KIRK,
SPEED INDICATOR,
APPLICATION FILED JULY 24, 1915.

1,190,298.

Patented July 11, 1916.

Inventor

F. S. Kirk

By *Watson E. Coleman*

Attorney

UNITED STATES PATENT OFFICE.

FRANK S. KIRK, OF ENID, OKLAHOMA.

SPEED-INDICATOR.

1,190,298.

Specification of Letters Patent. Patented July 11, 1916.

Application filed July 24, 1915. Serial No. 41,736.

To all whom it may concern:

Be it known that I, FRANK S. KIRK, a citizen of the United States, residing at Enid, in the county of Garfield and State of Oklahoma, have invented certain new and useful Improvements in Speed-Indicators, of which the following is a specification, reference being had to the accompanying drawings.

10 This invention relates to certain improvements in speed indicators, and it is an object of the invention to provide a novel and improved device of this general character whereby a signal, either audible or visual, is given upon the speed of the vehicle, to which the indicator is attached, being in excess of certain limitations.

Furthermore, it is an object of the invention to provide a novel and improved 20 device of this general character whereby the operator of the vehicle to which the improved indicator is applied may be warned that the travel of the vehicle is closely approaching a speed limit.

25 The invention consists in the details of construction and in the combination and arrangement of the several parts of my improved speed indicator whereby certain important advantages are attained and the 30 device is rendered simpler, less expensive and otherwise more convenient and advantageous for use, all as will be hereinafter more fully set forth.

The novel features of the invention will 35 be carefully defined in the appended claim.

In order that my invention may be the better understood, I will now proceed to describe the same with reference to the accompanying drawings, wherein is disclosed 40 a diagrammatic view illustrating an indicator constructed in accordance with an embodiment of my invention.

As disclosed in the accompanying drawings, 1 denotes the dial of a speedometer of 45 any ordinary or preferred construction and with which coacts the index or pointer 2, said index or pointer 2 being in electrical connection through the medium of the conductor *a* with a suitable source of electrical 50 energy, said source being either a battery *S* or a magnet *M*, said conductor coacting with either of said sources through the medium of a conventional switch *A*.

55 3 denotes a contact adjustably secured to the dial 1 and in electrical connection through the medium of the conductor *b* with

the signal 4 so positioned upon the vehicle as to be readily observed by passers-by so that when said signal, which is herein disclosed as a conventional incandescent lamp, 60 is burning indication will be given that the vehicle is traveling at a speed in excess of a predetermined limit.

In practice, I find it of particular advantage to employ a plurality of contact plates 65 3 so as to provide for the various speed limits as generally arranged for business districts, residential districts, suburban districts and State limits, and immediately preceding each of the contact plates 3 is 70 the smaller contact member 4 insulated from the adjacent plate or plates 3 and each of said plates 4 is in electrical connection through the medium of a conductor *c* with the buzzer *B* which upon sounding gives 75 notice to the operator of the vehicle that an excessive speed is being closely approached. The remaining plates 3 are in electrical connection through the conductors *d* and *e* with the signals 5 and 6 also preferably incandescent lamps and arranged in parallelism with the signal 6 is the audible signal 7, herein disclosed as a conventional electric bell. 80

In practice, I desire to have the signals 85 4, 5 and 6 of differing colors so that the various speeds of the vehicle may be readily determined and it will be observed that when the vehicle is traveling in excess of the highest speed limit, the audible signal 90] 7 will also be caused to operate. It will also be observed that as the index or pointer 8 passes from one plate 3 to a second plate that the previously burning lamp will be cut out so that at no time will there be more 95 than one of the signals 4, 5 or 6 in operation.

I do not wish to be understood as limiting myself as to the manner whereby the various electrical connections are afforded but, as herein disclosed, I have the circuits for 100 the lamps and the buzzer mounted, as indicated at *G*. As herein embodied, the first contact plate 3 reading from the left of the dial 1 gives indication when the speed limit of the business district is exceeded, the second plate 3 is intended to give indication when the speed limit of the residential district has been passed, the third plate is to give indication when the suburban speed limit or other special provision, such as 105 boulevards or the like, has been reached, while the fourth plate serves to give indi- 110

cation that the State speed limit has been reached.

From the foregoing description, it is thought to be obvious that a speed indicator constructed in accordance with my invention is of an extremely simple and comparatively inexpensive nature and is particularly well adapted for use by reason of the convenience and facility with which it may be 10 assembled, and it will also be obvious that my invention is susceptible of some change and modification without material departure from the scope of the appended claim and for this reason I do not wish to be understood as limiting myself to the precise arrangement and formation of the several parts herein shown in carrying out my invention in practice.

I claim:

20 In combination with a dial and index

of a speedometer, a source of electrical energy in communication with the index, a plurality of contact plates carried by the dial and with which the index is adapted to contact, said contact plates being arranged circular or concentric to the rotative axis of the index, alternate contact plates being of a length materially less than the intermediate contact plates, and a signal in electrical communication with each of the 30 contacts, the signal in communication with the alternate contact plates being audible and the signals in contact with the intermediate plates being visual.

In testimony whereof I hereunto affix my 35 signature in the presence of two witnesses.

FRANK S. KIRK.

Witnesses:

GUY S. MANATT,
HAROLD P. MOTT.
